UNITED STATES PATENT OFFICE

154,712

DESIGN FOR A TOOL BALANCER OR SIMILAR ARTICLE

Robert J. Robillard, Bryan, Ohio

Application October 31, 1947, Serial No. 142,249

Term of patent 14 years

(Cl. D52—1)

To all whom it may concern:

Be it known that I, Robert J. Robillard, a citizen of the United States and a resident of Bryan, in the county of Williams and State of Ohio, have invented a new, original, and ornamental Design for a Tool Balancer or Similar Article, of which the following is a specification, reference being had to the accompanying drawing, forming part thereof:

Figure 1 is a front elevational view of a tool balancer or similar article showing my new design, the rear elevation thereof being substantially identical to the front elevation.

Figure 2 is a side elevational view thereof, and Figure 3 is a bottom plan view thereof.

I claim:

The ornamental design for a tool balancer or similar article, substantially as shown and described.

ROBERT J. ROBILLARD.
